DESIGN FOR A CIGARETTE CASE WITH TRANSPARENT DISPLAY WINDOWS

Murray G. Gordon, New York, N. Y.

Application June 27, 1944, Serial No. 114,209

Term of patent 14 years

(Cl. D85—2)

To all whom it may concern:

Be it known that I, Murray G. Gordon, a citizen of the United States of America, residing at 1133 Broadway, New York, in the county of New York and State of New York, have invented a new, original, and ornamental Design for Cigarette Case with Transparent Display Windows, of which the following is a specification, reference being had to the accompanying drawing, forming part thereof.

In the drawing:

I claim:

The ornamental design for a cigarette case with transparent display windows, as shown.

MURRAY G. GORDON.
